HENRY R. DAVIES, OF TOLEDO, OHIO, ASSIGNOR TO INDUSTRIAL RESEARCH CORPORATION, OF TOLEDO, OHIO, A CORPORATION OF DELAWARE.

IGNITION SYSTEM.

1,372,650.

Specification of Letters Patent. Patented Mar. 22, 1921.

Application filed April 8, 1919. Serial No. 288,507.

To all whom it may concern:

Be it known that I, HENRY R. DAVIES, a citizen of the United States, residing at Toledo, in the county of Lucas and State of Ohio, have invented certain new and useful Improvements in Ignition Systems, of which I declare the following to be a full, clear, and exact description.

This invention relates to improvements in systems for generating electric current with power furnished by an internal combustion engine, and for utilizing the current, at least partially, in starting the engine and in furnishing ignition thereto.

One object of the invention is the provision of means for utilizing for ignition purposes, current from a comparatively high voltage dynamo-electric machine without the use of resistance coils or high capacity condensers.

Another object of the invention is the provision of means for supplying a relatively strong current to the ignition system, while the engine is being started.

Another object is the provision of means for supplying to the ignition circuit from the generator or motor-dynamo, a current which is stronger in proportion to the total current generated at comparatively low engine speeds than at high engine speeds.

Another object is to combine means for taking the ignition off the third brush of the generator or motor-dynamo, and means for taking current for the shunt field of the machine off the third brush also, which combines with the third brush regulation of the field, producing a comparatively high current output for the machine at low speeds, a third brush ignition circuit making a larger part of the total current output available for ignition at low speeds than at high speeds.

Other objects will appear as I proceed with the description of that embodiment of the invention, which for the purposes of the present application, I have illustrated in the accompanying drawing, in which:

Figure I is a diagram of apparatus and electrical connections showing my invention as applied to a motor-dynamo.

Fig. II is a similar view showing the invention applied to a two-unit system, that is one in which the motor and generator are separate machines.

Fig. III is a view similar to Fig. I, but

showing the motor-dynamo field extending across the main brushes instead of between one of said main brushes and an auxiliary brush.

Similar reference characters refer to similar parts throughout the views.

In each of the figures I have shown diagrammatically at 10 a storage battery electrically connected through a switch 11 with a load circuit, here illustrated as a bank of lamps 12. Circuit wires 13 and 14 connect the opposite terminals of the battery with the main brushes 7 and 8, of a dynamo-electric machine, which in Figs. I and III is illustrated as a motor-dynamo 15, while in Fig. II it is shown as a generator 16, a separate machine 30 being employed as a motor. In Figs. I and II the shunt field 17 is taken off the third brush 9 of the dynamo electric machine, but in Fig. III, I have shown a shunt field 18 connected across the main brushes 7 and 8 of the machine.

In each of the figures a circuit wire 19 leads from the third brush 9 to the primary winding 20 of an ignition coil of a gas engine, operatively connected with the motor-dynamo in Figs. I and III and with the motor in Fig. II, as indicated by the diagrammatically illustrated shaft 21. The other side of the primary coil is electrically connected by a circuit wire 22 with the circuit wire 13 and thence to the main brush 7 of the machine. In the primary ignition circuit, an interrupter 23 and a condenser 24 are arranged in parallel, for purposes well known to those skilled in the art. The secondary winding of the ignition coil is indicated at 25, it being connected through the conductor 26 with a current distributor 27 from which the high tension current is led to spark plugs 28 and thence to ground. The other side of the secondary winding is connected to ground at 29.

In Fig. II the engine starting motor 30 is bridged across the line wires 13, 14 when switch 31 is closed. The operation of a plunger 32 to close the switch 30 simultaneously closes a switch 33 in the circuit wire 13, but the parts are so arranged that the switch 31 may be opened without opening the switch 33. In this figure is shown, also, a battery cut-out of a common design. One coil 34 of the cut-out is connected in a shunt 35 across the line wires 13, 14. The second coil 36 is connected in the wire 13 when the cut-out ar-

ture 37 is in attracted position. When the generator 16 is producing current of a certain minimum voltage, the coil 34 sets up sufficient magnetism to attract the armature 37 thus closing the generator ignition circuit. Now that the armature 17 is attracted it is held down by coil 36 as well as coil 34, and hence the circuit is not broken until the voltage decreases to a point somewhat lower than that required to close the cut-out. In this way, constant opening and closing of the cut-out at a certain engine speed is avoided.

Regulation of a shunt field generator by means of a third brush, to which one terminal of the field is connected, is old and well known in the art. It is also old, as shown in Patent No. 801823 to E. J. Berg, to take current for an ignition circuit from a third brush, in order to obtain current of a proper voltage from a comparatively high voltage machine. So far as I am aware however, it is novel to take both the ignition current and the field from a third brush, and by doing so to obtain better regulation of the ignition than could be obtained by the use of either one alone. I also believe it to be novel to employ a third brush as one terminal of the ignition circuit of a gas engine, operatively connected to a motor-dynamo. In this latter connection a new and valuable result is obtained, namely a stronger ignition current during starting than during generating.

The first of the above named features of my invention is illustrated in Fig. II. When the operator depresses the plunger 32, both of the switches 31 and 33 close. The motor 30 draws current from the battery 10 and rotates the engine shaft 21. At the same time current is fed from the positive side of the battery through the circuit wire 14 to the brush 8 of the generator 16, and from the third brush 9 through the primary of the ignition back to the battery through circuit wires 22 and 13. When the engine begins to operate under its own power, after being revolved by the motor 30, and after it has acquired a predetermined speed, the voltage across the main brushes 7 and 8 of the generator rises sufficiently to cause the coil 34 of the cut-out to attract armature 37, and thereafter the ignition circuit draws its current from the generator instead of the battery. At the slower generator speeds, distortion of the field caused by the lines of force set up in the armature is small; hence the voltage drop across the brushes 7 and 9 is not much diminished by distortion. At greater speeds however, the distortion increases, the axis of commutation moving toward the right under the brush 7, and reducing correspondingly the voltage and current across the field winding 17, which in turn reduces the electro-motive force of the machine and thus the current traversing the

field winding 17 and the ignition coil 20, which, by weakening the field, further reduces the electro-motive force. The third brush connection of the field winding 17 therefore tends to make the total current output of the machine greater in proportion to its speed of rotation, at low engine speeds than at high engine speeds. Now, by connecting the ignition circuit also to the third brush, I utilize for ignition purposes a greater proportion of the total current output of the machine at low engine speeds than at high engine speeds. Here the amount of field distortion determines the amount of regulation, just as in the case of the field winding. In this way the effect upon the ignition current of the connection of the field circuit with the third brush, and the connection of the ignition circuit with the third brush, are cumulative.

In Figs. I and III the invention is illustrated in connection with a motor dynamo. Here, closing of the switch of the circuit wire 13 causes the dynamo-electric machine 15 to operate as a motor, drawing current from the battery 10, to start the gas engine through the operative connection 21. While the machine is motorizing, the distortion of the field, due to the lines of force set up by the armature current, is in a direction opposite to that of the distortion during generating. Furthermore, because of the fact that the load at this time is large and counter electro-motive force is small, a heavy current traverses the armature of the machine producing the greatest distortion of the field just at the beginning of the motorizing function. This field distortion is gradually decreased as the motor gets up speed. Consequently, the line drop between the brushes 7 and 9 is greatest at the beginning of the starting operation, and is greater at all times during motorizing than during generating by an amount corresponding to the sum of the angle of forward lead, when the machine is used as a generator, plus the angle of backward lead when it is used as a motor. The current through the primary winding 20 of the ignition coil is therefore greatest at the beginning of the motorizing of the machine 15, and proportionately greater during the balance of the time, while it is motorizing than while it is generating, which is highly desirable, as will be readily appreciated.

I am aware that the particular embodiment of my invention described, and illustrated in the accompanying drawing, is susceptible of considerable variation without departing from the spirit thereof, and therefore I desire to claim my invention broadly, as well as specifically, as indicated by the appended claims.

I claim as my invention:

1. In combination with a generator hav-

ing main brushes and an auxiliary brush, a shunt field for said generator and an ignition circuit, said field and circuit being connected in parallel and interposed between 5 said auxiliary brush and one of said main brushes between which the voltage diminishes with increase of speed.

2. In combination with a gas engine, a motor-dynamo operatively connected therewith, said motor-dynamo having main brushes and an auxiliary brush, a storage battery electrically connected to said main brushes, and a shunt field and an ignition circuit connected together in parallel and 10 interposed between said auxiliary brush and that one of said main brushes between which the voltage decreases as the dynamo speed increases, whereby maximum torque 15 for the motor and maximum ignition current for the engine is obtained at starting.

3. The combination with a generator having a shunt field, main brushes and an aux-

iliary brush, of an ignition circuit having a primary winding, said ignition circuit being connected to the auxiliary brush and 25 that one of the main brushes between which the voltage diminishes with increase of speed.

4. The combination with a motor-dynamo having a shunt field, main brushes, and an auxiliary brush fixed on the motor dynamo so that the voltage between the auxiliary brush and one of said main brushes diminishes with an increase in speed of the motor dynamo, of an ignition circuit, said ignition 30 circuit being connected to the main and auxiliary brushes between which the voltage diminishes with speed increase, whereby maximum ignition current is obtained at approximately lowest speeds, when the motor 35 dynamo is functioning as a motor.

In testimony whereof, I affix my signature.

HENRY R. DAVIES.
